UNITED STATES PATENT OFFICE.

JULIUS H. RICHARDS, OF ESSEX, NEW JERSEY, ASSIGNOR TO SPLITDORF ELECTRICAL COMPANY, OF NEWARK, NEW JERSEY.

ENGINE-STARTER.

1,227,003.

Specification of Letters Patent. Patented May 22, 1917.

Application filed July 21, 1915. Serial No. 41,203.

To all whom it may concern:

Be it known that I, JULIUS H. RICHARDS, a citizen of the United States, residing at Newark, in the county of Essex and State 5 of New Jersey, have invented certain new and useful Improvements in Engine-Starters, of which the following is a specification.

This invention relates to means for starting internal combustion engines by means 10 of an electric motor receiving its power from an external source, such as, a storage battery and also includes means for applying said external source of power to the electric motor and for disconnecting the 15 same, therefrom.

Another object of my invention is to provide positive means for engaging the starting motor to the engine and to provide quick and efficient means for disconnecting 20 the starting motor from the engine when the engine begins to operate under its own power.

A further object is to provide means for removing the source of power from the electric motor when the engine begins to operate under its own power even though the power applying means is still retained in the 25 position which causes the motor to begin its functions, thus putting the electric motor 30 under control of the engine and effecting a great saving in power.

An important feature of my invention is the method of mounting and operating the gear which engages the engine. In my companion application, Serial No. 877146, filed 35 December 14, 1914, I have shown and claimed broadly the fundamental principles to which my present application relates. In my present application, as well as in the 40 parent application, the armature shaft of the electric motor is hollow and supported in suitable bearings, thus allowing the armature to remain in a permanent position within its field whereby it is always in position to exert its greatest torque. Passing 45 through the hollow shaft and extending between the bearing end plates of the motor is a second shaft. One end of the hollow shaft drivingly carries a gear which however, is operatively connected to the second

shaft. This provides a very unique arrangement and gives an even more compact unit than that shown and described in my previous application heretofore referred to.

Other and further objects of my invention will be readily understood by persons skilled in the art from a consideration of the following description, taken in connection with the drawings, wherein like numerals refer to corresponding parts in the various figures.

Figure 1 is a side elevation of the electric motor, preferably of the series type, mounted on a portion of the engine frame work, with the driving gear and switching mechanism in their normal or idle positions.

Fig. 2 is a top plan view of Fig. 1.

Fig. 3 is a side elevation, similar to Fig. 1 but with the driving gear and switching mechanism in their working positions.

Fig. 4 is a top plan view of Fig. 3.

Fig. 5 is an end view of a portion of the switching mechanism connecting a mechanical element of the electrical circuit with the internal shaft of the motor.

Fig. 6 is a side view of Fig. 5.

Fig. 7 is an end view of one of the switch supports.

Fig. 8 is a side view of Fig. 7.

Fig. 9 is a sectional view of a compensating element of the switch.

Fig. 10 is a side view of an element of the switching device.

Fig. 11 is a sectional view of the driving gear and motor shaft with the internal shaft shown in full.

Fig. 12 is an end view of Fig. 11.

Fig. 13 is a diagram of the electrical circuit, including a part of the switching mechanism, the motor and source of power, said switch being shown in full lines in a position just as the gears go into engagement and in dotted lines should an obstruction be met with by the driving gear.

Referring now particularly to the drawings, 1 is a field frame of an electric motor, within which is mounted an armature 2 on a shaft 3 supported by bearings 4 and 5, carried by end plates 6 and 7. The electric

95

100

motor structure as above set forth is mounted on some part of the frame work of the engine or on a bracket 8, by means of bolts 13, the bracket being attached to the engine frame by any suitable means, such as bolts 9. The end bearing plate 6 is adapted to fit within an annular hole cut in the fly-wheel housing 10. 11 indicates a portion of the fly-wheel contained within the housing 10. 12 is any suitable packing, such as felt, for the purpose of keeping oil within the fly-wheel housing, since it is customary to use oil therein so that the fly-wheel will throw a certain amount of oil on to the gear teeth, cut integral with the fly-wheel or attached thereto. It is to be understood that the fly-wheel 11 has suitable gears cut thereon or fastened thereto.

The armature shaft 3 is hollow. Carried within the hollow portion is a second shaft 14, which extends at both ends of the electric motor between the end bearing plates. The armature shaft 3 has an extension 15 beyond the bearing 4 and this extension has splines 16 formed thereon, while the extreme end 17 is reduced somewhat in diameter to make a seat for spring 18. The outer end of the spring 18 rests against the collar 19 which is pinned to the shaft extension 15, by means of a pin 20. Mounted on the splines 16 is a gear 21, which has grooves 22 to correspond with said splines. Between two splines, the armature shaft 3 is slotted as indicated at 23. Passing through the gear 21 and the slot 23 and the inner shaft 14 is a pin 24 both ends of the pins 24 being riveted at the base of the teeth of gear 21 so as to maintain a permanent position and not disturb the operation of the gear. The function of slot 23 and the pin 24 will be made definite in the description of the switching mechanism which follows. Associated with the motor and preferably mounted on the top thereof is a box 25 which incloses the electrical switching mechanism shown in Figs. 2 and 4, the cover of said box being removed to show the parts in their various relations. The switching mechanism comprises two rods 26 and 27, which pass through the box 25. The rod 26 carries a switch contact 28 and rod 27 carries a switch contact 29, the arms of which are somewhat shorter than those of contact 28. Both of these switch contacts are insulated in any suitable manner from the switch rods 26 and 27. Switch blades 30 and 31 are securely attached to the sides of the box and properly insulated therefrom, contact studs 32 and 33 being used for connecting to the switch blades 30 and 31. On the end of rod 27 which I choose to designate as a pull rod is an adjustable fixture 34 to which suitable levers are connected for the purpose of operating

the pull rod. The pull rod may be operated by attaching a fixture 35 at the rear part of the switch box 25, as indicated in dotted lines, thus, if space should not permit the use of the fixture 34 in the position shown the rod 27 may be cut off in front 70 to the same length as 26 and an attachment made as indicated at 35 at the rear. The switch rod 26 has mounted thereon a pawl carrier 36, the rod 26 passing through the hole 37, in an extension 38, which is slotted 75 at 39 and set screws 40 are used to clamp the two parts of the extension 38 against the rod 26.

In order to guide the pawl carrier 36 as it is carried back and forth by the switch 80 rod 26, two studs 41 and 42 are attached to the motor frame and these studs pass through the holes 43 and 44 of pawl carrier 36. The lower portion of pawl carrier 36 is slotted as indicated at 45 and this slot 85 bridges the end of the inner shaft 14, between two collars 46 and 47, which are pinned to the shaft 14 by pins 48 and 49. It is seen that as the switch rod 26 moves forward and back, the shaft 14 is carried 90 with it or vice versa. The pawl carrier 36 has a slot 50 within which is mounted a pawl 51, by means of a pivot screw passing through the hole 52 in the pawl carrier and the hole 63 in the pawl. Mounted on 95 the pull rod 27 and directly over the pawl 51 is a device which I have called in my previous application heretofore mentioned, as a compensating device. This device is shown in Fig. 9 but since it is described and claimed in my previous application, it will be only briefly referred to here and then only for the purpose of making the operation of my present invention clearer. The compensating device 53 is for the purpose of 100 allowing pull rod 27 to have a certain movement forward should switch rod 26 be retarded or stopped. It has a shoulder 54 which in the normal position of the switching mechanism engages the notch 55 of the pawl 51. It will now be seen that when the pull rod 27 is operated, the pawl carrier 36 is moved along and the rod 26 is moved along with it on account of the shoulder 110 54 of the compensating device, engaging 115 the notch 55 of the pawl. The extreme end of the pull rod 27 passes through the hole 60 in a supporting member 56, which is carried on support rods 41 and 42 passing through the holes 57 and 58, being clamped 120 to said rods by suitable set screws 59.

I will now describe the operation of my device, the parts of which are shown in their normal or inoperative positions in Figs. 1 and 2. When it is desired to start the engine, the operator manipulates the intermediate levers running to the driver's seat (not shown) so as to produce a pull on

the rod 27. Since the compensating device 53 is in engagement with the pawl 51, as heretofore described, the pawl carrier 36 carries the rod 26 forward with the rod 27 and at the same time through the engagement with the extension of the inner shaft 14, this is also carried forward and the gear 21 with it. Since the gear is pinned to the shaft 14, as already explained, it is 10 carried forward to engage with the fly-wheel 11. On account of the spiral splines 16, the gear 21 and shaft 14 are given a rotary motion, thereby enabling the gear to readily find its way into engagement with 15 the gear teeth on the fly-wheel. The spring 18 and the collar 19 on the armature shaft extension 15 absorb the shock of the gear 21 as it goes into mesh with the fly-wheel gear. As the gear 21 engages the gear on 20 the fly-wheel, the switch contacts 28 and 29 which are carried forward by the rods 26 and 27, go into engagement with the switch blades 30 and 31 when the circuit through 25 the electric motor is completed and the motor will begin to crank the engine.

Should a tooth of the pinion meet a tooth of the fly-wheel, either of which for any reason has become buried on the edge, the compensating device 53 will then come into 30 action and allow the pull rod 27 to continue in its movement until the motor circuit is closed, as shown in dotted lines in Fig. 13. The closing of the motor circuit allows the armature 2 to turn and remove 35 or clear the obstruction so further pull on the rod 27 will cause gear 21 to go into mesh with the fly-wheel as described in my previous application but since it is only collateral with my present invention, further description is omitted.

Coincident with the meshing of the gear 21 with the fly-wheel and before the rod 27 reaches the end of its movement, the nose 61 of the pawl 51 engages a portion of the motor frame, slightly lower and between guides 62 and this serves to tilt the nose 61 of the pawl upward, releasing the notch 55 from the shoulder 54 of the compensating device 53 but by this time, the circuit through the 40 electrical motor has been completed and the armature 2 in turning holds the gear 21 in mesh and thereby maintains the rod 26 in its operative position. When the engine starts under its own power, the fly-wheel 11 turns 45 faster than the gear 21 and on account of the spiral splines 16, the gear 21 is carried out of mesh with the fly-wheel or from the position shown in Fig. 3 to that shown in Fig. 1. The gear 21 when it disengages from 50 the fly-wheel carries with it the shaft 14 and likewise the pawl carrier 36 and rod 26, thereby opening the motor circuit through the switch contacts 28 and 29 even though the operator may still have the pull rod 27

in its operated position. It is thus seen that 65 the minimum amount of power is taken by the act of cranking the engine, since the time of consuming power from the storage battery is controlled by the engine and not 70 by the operator.

Should for any reason there be something 75 the matter with the engine that it does not start, the parts may remain in the position shown in Fig. 3 with the exception of the pull rod 27, which on being released, returns 80 to the position of Fig. 2 through the action of the spring 64 thereby opening circuit to the electric motor and stopping the action of cranking. As soon as the trouble has been fixed, the rod 27 can be pulled directly 85 to the position of Fig. 4, when the electric motor is started and disengagement will take place as previously described.

On account of my method of engaging the 90 motor with the engine, it is not necessary to use a resistance in the armature circuit of the motor, as is generally done. This resistance often burns out, causing more or less trouble and I do away with this source of annoyance. By my method of engaging 95 the driving gear with the fly-wheel, I prevent clashing of gears in the starting operation. My present invention is intended as an improvement over my companion application, heretofore referred to, in the method 100 of mounting the driving gear and the means for engaging and disengaging the gear with the fly-wheel of the engine, together with improved switching means.

It will be apparent to anyone skilled in 105 the art that numerous changes and alterations may be made in the various details shown herewith, but such changes and alterations are believed to come within the scope of the appended claims.

Having thus described my invention, what 110 I claim is:

1. In an apparatus of the class described, the combination of an engine, a rotatable member driven by said engine, an electric motor having its armature in a substantially fixed axial position, a source of power, means for applying said source of power to said motor, a hollow shaft for said motor armature having an extension at one end, a gear wheel mounted on said extension and means passing through said hollow shaft and operated by the said power applying means for causing said gear wheel to engage 115 with said engine rotatable member.

2. In an apparatus of the class described, in combination, an engine, a member driven by said engine, a source of power, a rotatable armature and means for applying the 120 source of power thereto, a hollow shaft for supporting said armature and bearings therefor, said shaft having an extension at one end, a gear wheel mounted on said ex-

5 tension, an inner shaft within the hollow shaft and means associated with the inner shaft and operated by the said power applying means to cause said gear to engage said engine driven member, when said inner shaft is operated.

3. In an apparatus of the class described, in combination, an engine, a member driven by said engine, a source of power, a rotatable armature and means for applying the source of power thereto, a hollow shaft for supporting said armature and bearings therefor, said shaft having an extension at one end, spiral splines on said shaft extension, a gear wheel adapted to move rotatably and longitudinally on said splines, an inner shaft within the hollow shaft, a slot in said shaft extension substantially parallel to said splines, and means passing through said slot for fastening said gear wheel to said inner shaft and means for operating said inner shaft to cause said gear to engage with said engine driven member.

4. In an apparatus of the class described, in combination, an engine, a member driven by said engine, a source of power, a rotatable armature and means for applying the source of power thereto, a hollow shaft for supporting said armature and bearings therefor, said shaft having an extension at one end, spiral splines on said shaft extension, a slot in said hollow shaft between two of said splines, a gear wheel mounted on said shaft extension, a shaft within said hollow shaft, a pin passing through said gear and inner shaft and adapted to move in said slot, means for moving said inner shaft to carry said gear into engagement with said engine driven member and means on the end of said 40 hollow shaft for absorbing the shock of said gear as it engages with said engine driven member.

5. In an apparatus of the class described, in combination, an engine, a member driven by said engine, a source of power, a rotatable armature and means for applying the source of power thereto, a hollow shaft for supporting said armature and bearings therefor, said shaft having an extension at one end, a gear wheel mounted on said extension, a shaft within said hollow shaft, means connecting said gear to said inner shaft, means for moving said inner shaft longitudinally to cause engagement of said 55 gear with said engine driven member, means common to both the gear and said hollow shaft for holding the gear in engagement with said engine driven member while the same is being rotated, said means also serving to effect the release of said gear from said engine driven member at a predetermined speed of the latter.

6. In an apparatus of the class described, in combination, an engine, a rotatable mem-

ber driven by said engine, an electric motor 65 having an armature supported on a hollow shaft one end of which projects beyond its bearing, a second shaft supported within said hollow shaft, a driving gear on said hollow shaft extension and fastened to said 70 second shaft, means in said hollow shaft extension to allow said driving gear and second shaft to move longitudinally and rotatably, a switch associated with said motor and means interconnecting said switch and said 75 second shaft whereby when said switch is operated, said driving gear is connected with said rotatable member on said engine.

7. In an apparatus of the class described, in combination, an engine, a member driven 80 by said engine, a source of power, two rotatable members, one within the other, a gear drivingly associated with the outer of said two rotatable members but fixed to said inner rotatable member, manually operable 85 means for moving longitudinally the inner one of said rotatable members to cause said driving gear to engage with said first member, said manually operable means also serving to connect said source of power with the 90 outer of said two rotatable members to start said engine.

8. In an apparatus of the class described, the combination of an engine, a rotatable member driven by said engine, a source of 95 power, a rotatable member driven from said source of power and means for applying said source of power to said rotatable member, a third rotatable member within the second mentioned rotatable member, a driving gear 100 on said second member, means for fastening the driving gear to the third rotatable member whereby when said member is longitudinally moved said gear is caused to engage with the engine driven rotatable member. 105

9. In an apparatus of the class described, in combination, an engine, a member driven by said engine, a source of power, two rotatable members one within the other, a gear wheel drivingly connected with the 110 outer of said two rotatable members, means for fastening said gear wheel to the inner of said two rotatable members, means for moving longitudinally the said inner member to move said gear wheel into engagement with the engine driven member, said source of power being adapted to operate on the outer of said two members to start said engine.

10. In an apparatus of the class described, in combination, an engine, a rotatable member driven by said engine, an electric motor having an armature supported on a hollow shaft, one end of which projects beyond its bearing, a second shaft supported within 125 said hollow shaft, a gear drivingly associated with said hollow shaft extension but rigidly fastened to said second shaft, means

- in said hollow shaft to allow said gear and second shaft to move rotatably and longitudinally, a switch mounted on said motor, said switch having a pull rod and a switch rod, said switch rod being operatively connected to said second shaft, connecting devices between said pull and switch rods, whereby when said pull rod is rotated said gear is caused to engage the rotatable member on the engine and means for disabling said connecting devices before said pull rod reaches the end of its movement whereby said switch rod is left under the control of said engine, for the purpose described.
11. In an apparatus of the class described, the combination of an engine, a rotatable member driven by said engine, a source of power, a second rotatable member driven from said source of power and means for applying said source of power to said second rotatable member, a driving gear carried by said second rotatable member, a third rotatable member mounted within said second rotatable member, means for moving said third rotatable member longitudinally to cause said driving gear to engage the engine driven rotatable member, and means common to both the driving gear and the second rotatable member to hold the driving gear in working relation with the engine driven rotatable member when the engine is being turned, said means also serving to disconnect the driving gear from the engine driven member when said engine starts under its own power.
12. In an apparatus of the class described, the combination of an engine, a rotatable member driven by said engine, a source of power, a second rotatable member driven from said source of power, a switch for applying said source of power to said second rotatable member, a gear drivingly carried by said second rotatable member, a third rotatable member mounted within said second rotatable member, said switch having a pull rod and a switch rod, said switch rod being connected to said third rotatable member, connecting devices between said pull and switch rods, acting to keep said rods operatively connected until said gear is engaged with the engine driven rotatable member, means for disabling said connecting devices as soon as said gear engages with the engine driven rotatable member, means when said engine is being turned common to both the gear and second rotatable member to hold the driving gear in working relation with the engine driven member and the switch rod in its operative position after said connecting devices have been disabled, said means also serving to disconnect the gear from the engine driven member and to return said switch rod to its normal position.
13. In an apparatus of the class described,
- in combination, an engine, a member driven by said engine, a source of power, an electric motor having a rotatable armature, a hollow shaft for said armature and bearings therefor, a gear wheel drivingly connected to said armature shaft, a second shaft passing through said hollow shaft and operatively connected to said gear wheel, a switch, connecting devices between said switch and said second rotatable shaft, said switch being adapted when operated to cause said second shaft to move said gear wheel into engagement with said engine driven member and also to close the circuit between said source of power and said motor and further acting to open the circuit between the motor and source of power when the engine starts under its own power.
14. In an apparatus of the class described, the combination of an engine, an electric motor having an armature, a source of power for said motor, and switching mechanism for applying said source of power to said motor, said motor having two shafts, one within the other, the outer of said shafts carrying means adapted to be connected to said engine, the inner of said shafts adapted to be moved spirally and axially with respect to said outer shaft to carry said means into engagement with said engine for the purpose described.
15. In an apparatus of the class described, the combination of an engine, a member driven by said engine, two rotatable members one within the other, the inner of said members being adapted for longitudinal movement with respect to the outer member, means drivingly mounted on the outer of said two rotatable members adapted to connect with the engine driven member, and means including the inner rotatable member for moving the first mentioned means into connection with said engine.
16. In an apparatus of the class described, the combination of an engine, a member driven by said engine, a source of power, two rotatable members one within the other, the inner one of said two rotatable shafts being adapted for axial movement with respect to the outer one and said outer shaft being substantially free from axial movement, means drivingly mounted on one of said two rotatable members adapted to connect with the engine driven member, means including the other of said two rotatable members for moving the first mentioned means into engagement with said engine, electrical windings on the first mentioned one of said two rotatable members, said source of power being adapted to be connected to said windings to start said engine.
17. In an apparatus of the class described, the combination of an engine, a member driven by said engine, two rotatable mem-

- bers one within the other, means drivingly mounted on the outer of said two rotatable members adapted to move spirally and axially with respect thereto to connect with the engine driven member, a switch, connecting devices between said switch and the inner rotatable member for moving the first mentioned means into connection with said engine when said switch is operated.
18. In an apparatus of the class described, the combination of an engine, a member driven by said engine, two rotatable members one within the other but adapted for relative spiral and longitudinal movement, means drivingly mounted on the outer of said two rotatable members adapted to connect with the engine driven member, a switch, connecting devices between said switch and the inner rotatable member for moving the first mentioned means into connection with said engine when said switch is operated, a source of power adapted to be connected by said switch to the outer of said two rotatable members to crank said engine.
19. In an apparatus of the class described, the combination of an engine, a member driven by said engine, two rotatable members one within the other, means drivingly mounted on the outer of said two rotatable members adapted to connect with the engine driven member, a switch, connecting devices between said switch and the inner rotatable member for moving the first mentioned means into connection with said engine when said switch is operated, a source of power adapted to be connected by said switch to the outer of said two rotatable members to crank said engine, said connecting devices adapted to be disabled when connection is made with said engine, whereby when said engine starts under its own power, said source of power is disconnected from the outer of said two rotatable members.
20. In apparatus of the class described, in combination, an engine, a rotatable member driven by said engine, a source of power, two rotatable members in driving relation with each other, an armature winding upon one of said two rotatable members, a gear adapted to engage and drive said engine driven member, means associated with each of said two rotatable members for causing said gear to move longitudinally into mesh with the engine driven member, said means furnishing a driving connection between said gear and one of the said two rotatable members, a shock absorbing device mounted upon one of said two rotatable members, and operable means whereby the source of power is applied to the said armature winding.
21. In an apparatus of the class described, in combination, an engine, an engine driven member, a source of power, two rotatable members adapted for longitudinal and rotative movement relative to each other, a gear drivingly associated with one of the said two rotatable members but fixed to the other rotatable member, operable means for causing said driving gear to be moved longitudinally into engagement with said engine member, an armature winding mounted upon one of said two rotatable members, said operable means also serving to connect the said source of power to the armature winding, and a shock absorbing device mounted on one of the said rotatable members.
22. In combination, a non-self-starting engine, a self starting motor having two rotatable shafts one within the other, the outer of said shafts being adapted to be connected to said engine, a source of power for said motor, switching mechanism for connecting the outer of said shafts to said engine, and for connecting said power to said motor, operative means for drivingly connecting the inner shaft with the outer shaft, a compensating device associated with said switching mechanism whereby a part of same may be moved independent of the other parts to apply power to said motor should said outer shaft in being connected to said engine meet with an obstruction, for the purpose described.
23. In an apparatus of the class described, the combination of an engine, a member driven by said engine, a source of power, two rotatable members one disposed within the other, a gear wheel drivingly mounted on the outer of said rotatable members but fastened to the inner of said members, a switching mechanism, connecting means between the switching mechanism and said inner rotatable member whereby when said switching mechanism is operated to connect the source of power to said outer rotatable member for the purpose of actuating the same said inner rotatable member is actuated to carry the gear wheel thereon into engagement with said engine driven member, means co-operating between the said two rotatable members to effect a release of said gear wheel from engagement with the engine when the latter runs of its own power, and means associated with the switching mechanism to assist the last mentioned means in returning said gear wheel, switching mechanism, and connecting means to their normal inoperative position.
24. In an apparatus of the class described, the combination of an engine, a member driven thereby, a source of power, a rotatable member driven by said source of power, a second rotatable member disposed within the first rotatable member and drivingly associated therewith, means secured to the second rotatable member adapted to engage said engine member, a switch having a pull

rod and a switch rod, means whereby when a force is exerted on the pull rod said switch rod is moved to connect the source of power to the first mentioned rotatable member and 5 also said first mentioned means is moved to engage the engine member, and means

whereby when said force is removed said pull rod is automatically returned to its normal position regardless of the position of said switch rod.

10

In witness whereof, I affix my signature.

JULIUS H. RICHARDS.
